UNITED STATES PATENT OFFICE.

HARRY C. BASTER, OF BENTON HARBOR, MICHIGAN.

LOOSE-LEAF-FILING-SYSTEM POSTING-TRAY.

1,397,616.

Specification of Letters Patent.

Patented Nov. 22, 1921.

Application filed April 5, 1920. Serial No. 371,296.

To all whom it may concern:

Be it known that I, HARRY C. BASTER, a citizen of the United States of America, and a resident of Benton Harbor, Michigan, have invented a certain new and useful Improvement in Loose-Leaf-Filing-System Posting-Trays, of which the following is a specification.

This invention relates to posting trays or other similar apparatus for use in connection with card indexes or loose leaf filing systems. In certain respects, therefore, the invention is in the nature of an improvement on the construction shown and described in my prior application Serial No. 204,334.

Generally stated, the object of the invention is to provide an improved construction and arrangement which will obviate the necessity of using a sprocket chain or other similar devices for operating the roller which is employed for upsetting the cards or sheets in the file case.

Another object is to provide an improved construction and arrangement whereby the upsetting roller is shifted in one direction by a weight, automatically so to speak, during the operation of posting and shifting the cards or sheets in the file case, so that the operator or user is required to shift the roller in one direction only, the said weight then serving to pull the roller back to the other end of the posting tray and file case.

It is also an object to provide certain details and features of construction and combinations tending to increase the general efficiency and the desirability of a loose leaf filing system posting tray of this particular character.

To these and other useful ends the invention consists in matters hereinafter set forth and claimed and shown in the accompanying drawings, in which—

Figure 1 is a longitudinal section of a posting tray embodying the principles of the invention, showing the upsetting roller in its lowered position at the rear end of the structure or apparatus.

Fig. 2 is a side elevation of the structure shown in Fig. 1.

Fig. 3 is a view similar to Fig. 1, but showing the upsetting roller in its raised position near the front end of the structure, and showing the loose leaves or cards of the

filings system in position to be raised or upset by said roller.

Fig. 4 is a rear end elevation of said structure or apparatus.

Fig. 5 is a vertical section on line 5—5 in Fig. 3.

Fig. 6 is a horizontal section on line 6—6 in Fig. 1.

Fig. 7 is a detail sectional view showing another position of the upsetting roller.

Fig. 8 is a similar view showing said roller in a different position.

Fig. 9 is a detail view similar to Fig. 7, but showing the parts in different positions.

As thus illustrated, the invention comprises a body frame 1 mounted on front and rear legs 2 and 3 of any suitable character.

The side walls of said body frame are provided with upper tracks 4 and lower tracks 5, the upper tracks having gaps 6 therein, near the rear end of the structure, and the front ends of the tracks 4 having pivoted sections 7 which normally rest upon the front end portions of the tracks 5 for a purpose which will hereinafter more fully appear. The top of the body frame is provided with longitudinal slots 8 for the two upsetting rollers 9, which latter are mounted upon the transverse shaft 10 and spaced apart thereon to travel in said slots. Said shaft 10 is provided at its ends with wheels 11 which travel on the tracks 4 when the rollers move toward the rear end of the structure, and which drop down through the gaps 6 and then travel forward on the tracks 5 when the rollers are pulled toward the front end of the structure. For this purpose, therefore, a transverse member 12 is provided at its ends with wheels 13 which travel on the lower tracks 14 of the body frame. Said shaft 12 is also provided with pinions 15 which engage the racks 16 carried by the tracks 14, whereby the member 12 is always exactly at right angles to the said tracks. Arms 17 connect the shaft 12 with the shaft 10, and with this arrangement the shaft 10 and the arms 17 swing up and down to permit the wheels 11 to pass from the tracks 5 to the tracks 4, and then downwardly through the gaps 6 to the lower position again, as shown in Figs. 1 and 3. When the wheels 11 strike the under side of the pivoted track sections 7, the latter are raised, as shown in Fig. 9, and when these track sections fall back into normal position, the

wheels 11 then ride upwardly from the track sections 7, as shown in Fig. 8, so that the rollers 9 are finally in position to travel horizontally in the plane of the tracks 4, 5 toward the rear end of the structure or apparatus, until the rollers arrive at the point where the wheels 11 will again drop down through the gap 6, and the rollers are then moved to the left again.

- 10 The instrumentalities for shifting the rollers 9 back and forth are as follows: A transverse rod 18 is provided with a sheave 19, at the front of the structure, and a transverse rod 20 is provided with a sheave 21 at 15 the rear end of the structure. The cord or flexible connection 22 has one end thereof attached to the body frame at 23, and has its other end attached to the shaft 12, after passing over the sheave 19, being also arranged around the sheave 24 which is carried by the bail-shaped member 25 which is hinged at 26 on the lower edges of the side portions of the main body frame. A similar cord or flexible connection 27 has one end 25 attached to the shaft or axle 12, and has its other end attached at 28 to the rear portion of the body frame, it being arranged to engage the sheave 21 previously mentioned, and also the sheave 29 which supports the 30 weight 30, whereby the rollers 9 are subject to a constant pull (by said weight) which tends to move them toward the rear end of the posting tray structure, and into the position shown in Fig. 1. When the leaves or 35 cards to be posted, and to be upset by the rollers, are in place in the file case 31, which may be of any suitable character, the operator or user presses downward on the bail-shaped member 25, thus pulling the rollers 40 9 forward to the position shown in Fig. 7, so that the wheels 11 will pass under the pivoted track section 7, and so that thereafter these wheels are free to ride upwardly upon these pivoted track sections, under the influence of the weight 30, as shown in Fig. 8, 45 thus bringing the rollers 9 into the positions shown in Fig. 3; and when in this position, the said rollers are held against displacement by the weight of the leaves or cards in 50 the file case. As fast as the leaves or cards are shifted toward the front of the posting tray the rollers 9, being subject to the pull of the weight 30, will shift toward the rear end of the posting tray structure. Each 55 time the rollers move toward the rear end of the posting tray—that is to say, toward the gaps 6, several of the leaves or sheets or cards are upset or raised, as shown in Fig. 3, thus making it possible for the operator 60 or user to more conveniently manipulate the said sheets or cards, one at a time, in a manner that will be readily understood. Any suitable means can be employed for supporting the leaves or sheets or cards in the file 65 case, the latter being supported by the ledges

31 at the top of the body frame of the posting tray structure.

Thus, as previously stated, the rollers 9 are manually movable in one direction toward the front of the posting tray structure, but are automatically movable in the opposite direction, by the pull of the weight 30, so that after the rollers are raised into operative position, nothing further is then necessary on the part of the operator or user, inasmuch as the mere manipulation and shifting of the sheets or leaves or cards themselves serves, in effect, to release the rollers from time to time, so that said rollers gradually approach the rear end of the posting tray structure.

With this construction and mode of operation, no sprocket chains are necessary, the rollers 9 being shifted through the medium of the flexible connections 22 and 27, in the manner explained, and the construction and mode of operation are thus reduced to a very simple and practical form or character, so that the structure is comparatively inexpensive to manufacture. The axis of the rollers 9 is always at right angles to the tracks by which they are supported, inasmuch as the pinions 15 and the racks 16 keep the shaft or axle 12 exactly at right angles to said tracks, said pinions being fixed on said shaft 90 12, so that one pinion can never rotate faster than the other. When the leaves are all shifted, the rollers 9 will then move of their own accord, under the influence of the weight 30, to the position where the wheels 11 will drop down through the gaps 6, and in this way, the apparatus is automatically restored to normal condition when the last of the leaves are finally transferred to the front of the drawer.

It will be understood, of course, that in practice the upset leaves are taken out one by one and posted, suitable entries being made thereon, and when returned they are placed at the front of the drawer, so that the roller keeps moving gradually back toward the rear end of the drawer, thus upsetting a few of the leaves at a time, until the user or person doing the posting has completed the work.

What I claim as my invention is:—

1. In a device of the class described, means for supporting a filing drawer thereon, and means associated with said means for upsetting leaves in said drawer when the drawer is supported on the first named means, in combination with instrumentalities for automatically operating said upsetting means, whereby the latter are, by the manipulation or shifting of the leaves, caused to move intermittently toward the rear end of the filing drawer.

2. The combination of a receptacle for holding leaves or sheets or cards in a more or less upright position, with their upper

- edges substantially even or flush, upsetting means to engage the lower edges of said leaves or sheets or cards, and instrumentalities whereby said means are movable into 5 position to raise some of said leaves or sheets or cards to bring the upper edges thereof above the others, said instrumentalities including front and rear flexible connections and parallel tracks for controlling the back 10 and forth movements of said means, devices for manually controlling the front flexible connection, and means for automatically controlling the rear flexible connection, so that said upsetting means are 15 manually movable in one direction and automatically movable in the opposite direction.
3. A structure as specified in claim 1, said upsetting means comprising one or more 20 rollers arranged to engage the lower edges of said leaves.
4. A structure as specified in claim 2, said upsetting means comprising one or more rotary members arranged to engage the lower 25 edges of said leaves.
5. A structure as specified in claim 2, said tracks comprising upper and lower parallel sections, pivoted end sections for the upper 30 tracks, with gaps in said upper track sections, said pivoted sections being normally inclined to rest upon the lower track sections, and said upsetting means having supporting elements which travel on said tracks and which travel under and raise said pivoted track sections and then move upwardly 35 on the latter to transfer the upsetting means from the lower tracks to the upper tracks, and said supporting elements being adapted to fall through said gaps to transfer said 40 upsetting means from the upper tracks to the lower tracks.
6. A structure as specified in claim 1, in which the instrumentalities for moving the upsetting means include racks and pinions 45 to maintain the axis of said upsetting means at right angles to said tracks.
7. A structure as specified in claim 2, in which the instrumentalities for moving the upsetting means include, racks arranged 50 parallel with said tracks, and means forming an axis for said upsetting means, and pinions mounted on said axis and engaging said racks to maintain the axis of said upsetting means at right angles to said tracks.
- 55 8. The combination of a receptacle consisting of a filing drawer for holding leaves or sheets or cards in a more or less upright position, with their upper edges substantially even or flush, a table on which the 60 drawer is adapted to be supported, means on said table to engage the lower edges of said leaves or sheets or cards, and instrumentalities whereby said means is movable into position to raise some of said leaves or sheets 65 or cards to bring the upper edges thereof above the others, said means including a roller having a horizontal axis of rotation, and said instrumentalities including devices to move said roller back and forth below the group of leaves or sheets or cards in said 70 receptacle, said devices including means to manually move the roller toward the front of the receptacle, and means to automatically move the roller toward the rear end of said receptacle. 75
9. The combination of a receptacle consisting of a filing drawer for holding leaves or sheets or cards in a more or less upright position, with their upper edges substantially even or flush, a table on which the drawer is adapted to be supported, means on said table to engage the lower edges of said leaves or sheets or cards, and instrumentalities whereby said means is movable into position to raise some of said leaves or sheets or cards to bring the upper edges thereof above the others, said means including a roller having a horizontal axis of rotation, and said instrumentalities including parallel tracks for supporting the axis of said roller in one 80 horizontal plane while moving toward one end of the receptacle and other tracks which support said axis in a lower horizontal plane while moving toward the other end of the receptacle, in combination with a flexible 85 connection to move said roller toward the front of the said receptacle, means whereby to manually control said flexible connection and an automatically controlled flexible connection to move said roller toward the rear 90 end of said receptacle. 95
10. The combination of a receptacle consisting of a filing drawer for holding leaves or sheets or cards in a more or less upright position, with their upper edges substantially even or flush, a table on which the drawer is adapted to be supported, means on said table to engage the lower edges of said leaves or sheets or cards, and instrumentalities whereby said means is movable into position to raise some of said leaves or sheets or cards to bring the upper edges thereof above the others, said receptacle having a longitudinal slot in the bottom thereof, and said means including a roller movable in 100 said slot, in combination with a front flexible connection, means whereby said connection is manually controllable to move said roller toward the front of the receptacle, and an automatically controlled rear flexible connection to move said roller toward the rear 105 end of the receptacle. 110
11. The combination of a drawer adapted to contain leaves or sheets or cards arranged with their upper edges substantially flush, 115 having means whereby the leaves or sheets or cards may be spread apart to facilitate inspection thereof, a table to support said drawer, a member movable along the top of said table to elevate some of said leaves or 120 cards to bring the upper edges thereof above the others, said means including a roller having a horizontal axis of rotation, and said instrumentalities including devices to move said roller back and forth below the group of leaves or sheets or cards in said 125 receptacle, said devices including means to manually move the roller toward the front of the receptacle, and means to automatically move the roller toward the rear end of said receptacle. 130

sheets or cards above the others, instrumentalities on said table to move said member back and forth below said drawer, and guides for said member, said instrumentalities comprising a front flexible connection having one end connected to said table and its other end connected to said member, a bail-shaped member for operating said flexible connec-

tion, a second flexible connection having one end thereof connected to said member and having its other end attached to said table, and means for constantly exerting a pull on said second flexible connection, so that when in use said member tends constantly to move toward the rear end of the table. 10

HARRY C. BASTER.
